US00D930915S

(12) **United States Design Patent** (10) **Patent No.:** **US D930,915 S**
Wu (45) **Date of Patent:** **** Sep. 14, 2021**

(54) **PET FEEDER**

(71) Applicant: **Changli Wu**, Linyi (CN)

(72) Inventor: **Changli Wu**, Linyi (CN)

(**) Term: **15 Years**

(21) Appl. No.: **29/773,072**

(22) Filed: **Mar. 5, 2021**

(30) **Foreign Application Priority Data**

Dec. 4, 2020 (CN) 202030746929.5

(51) **LOC (13) Cl.** **30-07**

(52) **U.S. Cl.**

USPC **D30/122**

(58) **Field of Classification Search**

(57) **CLAIM**

The ornamental design for a pet feeder, as shown and described.

DESCRIPTION

FIG. 1 is a perspective view of a pet feeder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
